UNITED STATES PATENT OFFICE.

WILLIAM HARPER, JR., OF PORT WASHINGTON, NEW YORK.

MEANS FOR INCREASING THE SPEED OF BOATS.

Application filed April 21, 1927. Serial No. 185,457.

This invention relates to means for increasing the speed of boats by reducing the friction encountered in passing through the water.

5 An object of the invention is to distribute a film of air uniformly in thin streams over the submerged surfaces of a boat to facilitate its propulsion through water.

It is a common practice to introduce a 10 stratum of air between the water and the bottom of a boat in order to reduce the friction produced by the immersed surfaces passing through the water. This is usually accomplished by forcing the air continuously through apertures in the bottom of the boat either by suction or by suitable blowing apparatus. The air acts as a cushion which diminishes the friction of the water when the boat is in motion.

20 The various constructions heretofore employed to increase the speed of a boat in this manner have proved inefficient because of their failure to diffuse the air evenly over the entire submerged surface of the boat, 25 thereby failing to effect a uniform reduction of water friction. The air has usually been fed through outlet ports or scales in the hull of the boat without regard to its direction or uniform distribution. Attempts 30 to supply air to all parts of the submerged hull have also frequently resulted in employing an excessive number of projecting outlet ports which offer more resistance to the motion of the boat than an ordinary 35 plane surface would do.

The difficulties outlined above are largely overcome by the present invention which provides a simple and efficient construction for laying a uniform thin film of air between the water and the submerged hull, rudder and propeller of a boat. This is accomplished by passing the air through spaced rows of uniform delivery orifices which open toward the stern of the boat. 45 In the preferred embodiment of the invention the delivery orifices comprise small parallel corrugations communicating with air intake ports whereby uniform thin streams of air are drawn from bow to stern 50 when the boat is in motion. The novel construction and arrangement of the air delivery orifices results in a more uniform reduction of water friction than heretofore and reduces the necessary under-water projecting 55 parts to a minimum.

The various features and advantages of the invention will be described in connection with the accompanying drawings in which similar reference characters designate corresponding parts in the several views, and in 60 which:

Fig. 1 is an inverted plan view showing the bottom of a speed boat embodying my invention;

Fig. 2 is an elevation showing a series of 65 air tubes communicating with delivery orifices in the bottom of the boat;

Fig. 3 is a detail sectional view showing the construction of air tube, air manifold and delivery orifice;

Fig. 4 is a fragmentary cross-sectional view looking through the hull;

Fig. 5 is a fragmentary elevation of the stern of the boat showing the construction of the rudder and screw propeller;

Fig. 6 is a section through the rudder, taken on the line 6—6 of Fig. 5;

Fig. 7 is a view of the upper part of one of the propeller blades; and

Fig. 8 is a section through the propeller 80 blade taken on the line 8—8 of Fig. 5, showing the air chamber and delivery port.

In the drawings, the invention is illustrated as applied to a speed boat having a hull 1 with a substantially flat bottom planking 2 and an interior reinforcing plate 3 of any suitable construction. A step 4 may be provided near the center of the boat to aid in retaining the air, but is not essential to the invention.

90 In the preferred embodiment of the invention thin streams of air are distributed uniformly over the bottom of the boat through air tubes 5 which project in substantially vertical planes above air manifolds 6. The 95 air manifolds extend transversely across the bottom of the boat and are attached to the reinforcing plate 3 by means of screws 7. Each air manifold 6 communicates through a series of ducts 8 with an air distributor 100 passage or groove 9 extending transversely through the bottom planking 2 under the air manifold. Continuous metal strips or ribs 10 extend transversely across the bottom planking 2 immediately under the distributor grooves 9. These strips or ribs are 105 preferably narrow, and may be widely separated from each other, as shown in Fig. 1. The forward end of each rib 10 is flat and lies flush with the bottom planking 2 while 110

the rear end is crimped or serrated to provide a plurality of closely spaced corrugated or fluted delivery orifices 11 which project toward the stern of the boat. The elongated strips of metal 10 are flexible and may be bent as required to fit the hull of the boat. The forward flat or smooth edge of the strips may be attached to the bottom planking 2 on one side of the opening 9 in any suitable manner. The corrugations taper toward the attaching edge of the strip, and the upper edges or peaks of the corrugations contact with the bottom planking 2 thereby closing the sides of the air delivery orifices 11, as shown in Figs. 3 and 4. The corrugations increase the rigidity of the strips 10, and serve to bring the converging streams of air and water into the closest possible proximity in relation to their respective areas.

When the boat is in motion the suction caused by the boat gliding over the water will cause air to be sucked through the air tubes 5, air manifold 6, ducts 8 and delivery orifices 11. Due to the shape and relatively close spacing of the delivery orifices 11 the air will emerge in strong wedge-like streams and be diffused evenly across the width of the boat. The width of the boat varies from bow to stern and the metal ribs 10 are preferably tapered slightly from bow to stern as shown in Fig. 1 so that the delivery orifices 11 on each side of the center line will point outwardly in substantially parallel planes. In this manner the film of air will spread out fan-like and cover the entire under surface of the boat following the water lines leaving the various surfaces. The corrugations not only direct air evenly under the hull and prevent the air from being forced toward the sides of the boat, but they also prevent the water from moving sidewise under the boat which would tend to displace the air film. The strips 10 slope gradually from the front to the rear edge and hence there are no abrupt projections which might tend to retard the passage of the boat through the water. The size and relative spacing of the air manifolds 6 and corrugated metal ribs 10 will vary according to circumstances. They are preferably spaced closely enough together to maintain strong streams of air from one series of delivery orifices to the next so that a uniform thin cushion of air will envelop the entire submerged surface of the hull. The delivery orifices may be spaced still further apart on either side of the step 4 since the cushion of air will be more readily retained under the stepped portion of the hull and forced toward the stern when the boat is in motion. The air tubes 5 project high enough above the water line to prevent the ingress of water which rises in the air manifolds and tubes when the boat is at rest.

In Figs. 2 and 5 a screw propeller 12 is shown mounted upon a shaft 13 which is connected with an engine inside the boat. The rudder 14 is supported by the rudder post 15 in the usual manner. According to the present invention the friction of the water on the rudder is reduced in a manner similar to that described above in connection with the hull. The rudder is provided with an air chamber 16 which communicates with the outer air through intake ports 17 on both sides of the rudder above the water line. The rudder is provided with a curved shield 18 extending lengthwise of the rudder post and having a series of small fluted air delivery orifices 19 disposed in substantially parallel planes and communicating with the air chamber 16. The shield 18 may be of any desired length, depending upon circumstances, but is preferably long enough to distribute a film of air over the greater part of the submerged sides of the rudder. When the boat is in motion air is sucked through the intake ports 17, air chamber 16 and the delivery orifices 19 on both sides of the rudder, the air emerging from the orifices 19 in strong wedge-like streams. The air is thus distributed uniformly over the submerged surfaces of the rudder.

Uniform streams of air are also distributed over the blades of the screw propeller 12 as shown in Figs. 5, 7 and 8. A series of small parallel fluted air outlets 20 are provided near the edge of the leading and compression side of the propeller blades communicating with hollow air chambers 21. A hollow channel 22 extending longitudinally through the propeller shaft 13 has one end communicating with the air chambers 21 and the other end communicating with a suitable intake port (not shown) inside the boat. When the propeller is turning air is sucked through channel 22 and air chambers 21 through the air outlets 20 and is distributed in a uniform thin film over the entire front faces of the propeller blades. In this manner, the retarding effect of skin friction is largely overcome and the efficiency of the propeller is greatly increased.

The invention is capable of various modifications and adaptations which are not specifically described but are included within the scope of the appended claims.

The invention claimed is:

1. The combination with a boat comprising a hull having a bottom surface, of a plurality of widely separated ribs extending transversely across said bottom surface, a plurality of closely spaced corrugations in said ribs having their forward edges closed and their rear edges opening toward the stern of the boat, and air inlet ports communicating with said corrugations.

2. The combination with a boat comprising a hull, of a plurality of continuous strips

- of material extending transversely across the bottom of said hull with their forward edges lying flat against the hull and their rear edges corrugated to provide a plurality 5 of orifices opening toward the stern of the boat, air chambers extending transversely across said hull and communicating with said orifices, and air intake tubes leading from said chambers to the atmosphere.
- 10 3. The combination with a boat having a hull, of a plurality of rows of air delivery orifices extending transversely across said hull, air distributor grooves formed in said hull and communicating with said delivery 15 orifices, air chambers extending transversely across said hull and communicating with said distributor grooves, and air intake tubes leading from said chambers to the atmosphere.
- 20 4. The combination with a boat having a hull, of a strip of material extending transversely across the hull with its forward edge flat against the hull and its rear portion crimped to provide a plurality of air delivery 25 orifices opening toward the stern of the boat, and means for supplying air to said orifices.
5. The combination with a boat having a hull, of a strip of material extending transversely across the hull with its forward edge flat against the hull and its rear portion crimped to form small parallel corrugations providing air delivery orifices opening toward the stern of the boat, and an air intake port communicating with a plurality of said orifices to permit air to be sucked through when the boat is in motion.
6. The combination with a boat having a hull, of a strip of material extending transversely across the hull with its forward edge flat against the hull and its rear portion crimped to provide a plurality of air delivery orifices opening toward the stern of the boat, an air distributor passage formed in 40 the hull above said delivery orifices, and air intake ports communicating with said passage to permit air to be sucked through said orifices when the boat is in motion.
7. The combination with a boat having a hull, of a plurality of narrow strips of metal extending transversely across the hull with their forward ends flush with the hull and their rear portions corrugated to provide a plurality of independent air delivery orifices 45 opening toward the stern of the boat, air distributor passages extending transversely
- through the hull above said metal strips and communicating with the air delivery orifices therein, air manifolds extending transversely across the inside of the boat above said air distributor passages, a plurality of spaced ducts extending through the hull and connecting said air distributor passages to the respective air manifolds, and air tubes leading from said air manifolds to the atmosphere. 60
8. The combination with a boat comprising a hull varying in width from bow to stern, of a plurality of continuous strips of material extending across said hull tapering at the center from bow to stern and having closely spaced air delivery orifices therein, and air intake ports communicating with said delivery orifices to permit streams of air to be sucked fan-like across the hull when the boat is in motion. 65
9. The combination with a boat having a hull, of a strip of material extending across said hull having a multiplicity of closely spaced air delivery orifices opening toward the stern of the boat with their forward and side edges closed, and an air passage communicating with said orifices to permit air to be sucked through when the boat is in motion. 70
10. A device for increasing the speed of boats comprising an elongated strip of flexible material having one edge adapted to be transversely attached to the under surface of a boat and provided with corrugations running transverse to said strip and tapering toward said attaching edge to provide a series of air passages for drawing air from the interior of the boat and discharging it in a film along the bottom of the boat beyond said strip. 75
11. A device for increasing the speed of boats comprising an elongated strip of metal adapted to span a transverse opening in the bottom of a boat, one edge of said strip being adapted for attachment to the under surface of the boat on one side of said opening, and corrugations formed transversely in said strip tapering toward said attaching edge to contact with the surface on the opposite side of said opening to provide a series of air passages. 80
